UNITED STATES PATENT OFFICE.

JOHN B. MERKELS, OF CHICAGO, ILLINOIS.

CLOSURE FOR ENVELOPS OR BAGS.

No. 877,789.

Specification of Letters Patent.

Patented Jan. 28, 1908.

Application filed June 14, 1906. Serial No. 321,724.

To all whom it may concern:

Be it known that I, JOHN B. MERKELS, citizen of the United States, residing at Chicago, in the county of Cook and State of Illinois, have invented new and useful Improvements in Closures for Envelops or Bags, of which the following is a specification.

This invention relates to closures for bags and envelopes, and it is designed to provide simple and efficient means for closing such articles without sealing the same against inspection.

Metal fastening clips of known construction are employed for the purpose of holding the closures, and the envelopes or bags may be put on the market each one having a clip attached, or without any clip at all, the clips to be provided by the user. With an ordinary envelop designed to hold circulars, pamphlets, booklets or other matter more or less bulky, or with bags in which merchandise is to be mailed, such as grain or seeds, the mouth of the envelop or bag can not well be closed by a paper clip or clasp, because of the tendency to tear the envelop and because the contents tend to work against the clip during transit or in handling, so that the clip is apt to be forced off, in which event the envelop opens and the contents fall out.

In this invention, a strip is provided on the back or side of the envelop, and the flap or end of the envelop or bag is folded down upon the strip, and the parts folded together and fastened by a paper clip or clasp, so that the contents of the envelop or bag do not work against the clip but against the flap or closure at the end thereof. With this device, no matter how bulky the envelop or bag is, a clip can be used to hold it closed.

The particular features of the invention will be evident from the following description and the accompanying drawings. In the drawings, two forms of the invention are shown.

Figure 1 is a perspective view of an envelop, open. Fig. 2 is a similar view, folded or closed. Fig. 3 is a similar view of the same, closed. Fig. 4 is a section on the line 4—4 of Fig. 3. Figs. 5 and 6 are perspectives of the invention applied as a bag closure, in open and partly closed positions, respectively. Fig. 7 is a similar view of the same closed.

The forms shown in Figs. 1 to 4, inclusive, are particularly adapted for envelop closures, and those shown in the remaining figures for

bag closures. Referring to the former, 6 indicates the front of an envelop and 7 the back. 8 is the flap, which may be made square, triangular, or any other shape, and in addition to its fold on the line 8^a, at the top of the envelop, it is also folded on the line 8^b, as hereinafter described.

The essence of the invention consists in attaching or forming a strip on one side of the envelop or bag, preferably the back, to the lower edge of which the flap can be fastened by means of a paper fastener after the flap and strip are folded together. In the form shown in Fig. 1 such a strip is shown at 9, and this is made by turning down the top or upper end of the back 7 and securing the strip to the back by means of gum as indicated at 10, leaving a detached space between the ends. The strip 9 folds upon the lines 9^a and 9^b forming two folds which envelop or inclose the folds of the flap 8. In closing this form the flap 8 is folded down, on the line 8^a, upon the strip 9. Said strip is of greater width than the flap, so that when then folded up on the line 9^b the lower end of the strip folds over the lower edge of the flap. Then the flap and strip are both folded together, on the lines 8^b and 9^a, to the form shown in Fig. 3. A paper clip 11 is then applied to the fold at the lower edge thereof, one branch of the clip entering under the folds to the detached space between the gummed portions 10 and the other branch of the clip lying upon the outside of the fold, so that the whole fold is gripped and held by the clip. One or more such clips can be applied, according to the length of the envelop or the nature of its contents. The fastening so formed enables the clip to be removed and the contents of the envelop inspected, which is desirable in mailing circulars, booklets and other printed matter, or merchandise of any kind.

With respect to bags or envelopes designed to contain merchandise, especially such as grain or seeds, it is desirable that both the front and back of the bag be of the same height, or so as to match around the mouth of the bag, whereby said front and back can be folded down together at the top, to form a closure which will not readily leak. Thus, in Figs. 5, 6 and 7, one side, which may be called the front of the bag, is indicated at 6, and the back at 7. The strip 9 is similar to the strip used with the envelop,

as above described, but instead of being formed integral with the back of the envelop, it is a separate piece of paper, attached to the back of the bag by gum at the 5 upper corners, as at 10. The same detached space is left between the gummed portions, and the strip also folded on the two lines 9^a and 9^b. The front 6 and back 7 of the bag fold together above the strip 9, on the lines 10 7^a and 7^b, and to form a closure said parts 6 and 7 are brought together at the top and folded down on the line 7^a upon the strip 9, the lower end of which is then folded up, on line 9^b, and over the mouth of the bag. Then 15 all parts are folded together upon the lines 7^b and 9^a to produce the complete fold. The clip 11 is then applied to the fold in the same manner as above described.

The invention is not limited to the exact 20 form shown. Instead of the square form shown, the envelop flaps can be cut off triangularly, as with an ordinary envelop. The strip 9 may be made of any length desired, and may be attached at any points 25 along the length of the strip, and the unattached space for the clip may accordingly be placed anywhere along the length of the strip, but the fastening holds best when the strip is attached at its ends, leaving the middle portion free for the clip or clips employed. The contents of an envelop or bag provided 30 with the closures described cannot leak out. The invention avoids the use of metallic fasteners which penetrate or produce holes in 35 the envelop or bag, and consequently it can be repeatedly used if desired.

I claim:

1. A closure for a paper receptacle, comprising a strip attached at its ends to one side 40 of the receptacle and having an intermediate unattached part, part of the receptacle, at the mouth thereof, being folded down upon and within said strip when closed, and a clip

embracing the fold and extending under the strip, at said unattached part. 45

2. A closure for a paper receptacle, comprising a strip secured at its upper corners to one side of the receptacle below the mouth thereof, the strip having an unattached part between and below said corners, part of the receptacle at the mouth thereof being folded down upon and in together with the lower part of said strip, and a clip embracing said fold and extending under between the strip and the receptacle, at said unattached part. 50 55

3. A closure for an envelop or bag, comprising a flap at the mouth thereof, a strip secured at its ends to one side of the receptacle, below the mouth thereof and unattached between said ends, the flap being folded within 60 and together with the strip, and a spring clip engaging and embracing the fold at the inner edge thereof and extending under the strip, between the ends thereof.

4. A closure for a paper receptacle, comprising a strip secured at its upper corners to the side of the receptacle below the mouth thereof and unattached between said corners and having a lower unattached portion, the top of the receptacle being folded down upon 70 said strip, and the latter being folded up around said part and over the mouth of the receptacle, forming a closed fold at the upper edge thereof, and a spring clip having branches between which the fold is embraced, said clip 75 being applied to the lower edge of said fold, with one of its branches extending under the same, between the strip and the body of the receptacle.

In testimony whereof I have signed my 80 name to this specification in the presence of two subscribing witnesses.

JOHN B. MERKELS.
